UNITED STATES PATENT OFFICE.

WILSON E. SYMONS, OF NEW YORK, N. Y.

DESIGN FOR AN ELECTRIC-WELDING AUTOTRUCK.

53,385.

Specification for Design.

Patented May 27, 1919.

Application filed October 28, 1916. Serial No. 128,333. Term of patent 7 years.

To all whom it may concern:

Be it known that I, WILSON E. SYMONS, a citizen of the United States, residing at New York, in the county of New York and State of New York, have invented a new, original, and ornamental Design for an Electric-Welding Autotruck, of which the following is a specification, reference being had to the accompanying drawings, forming a part thereof.

Figure 1 is a side elevation of the electric welding auto truck, showing my new design.

Copies of this patent may be obtained for five cents each, by addressing the "Commissioner of Patents, Washington, D. C."

Fig. 2 is a top plan view of the same.
I claim:

The ornamental design for an electric welding auto truck, substantially as shown.

In testimony that I claim the foregoing as my own, I have hereto affixed my signature in the presence of two witnesses.

WILSON E. SYMONS.

Witnesses:

ALFRED MUSCOTT,
JOHN J. WARD.
